AUTOMATIC FUEL INTERRUPTING DEVICE
FOR EXPLOSION ENGINESGeorge Carol Schuele von Hilvety,
Buenos Aires, ArgentinaApplication March 13, 1936, Serial No. 68,754
In Argentina September 7, 1935

12 Claims. (Cl. 123—97)

This invention relates to improvements in fuel interrupting devices, applied to carburetors.

The improvement consists in utilizing the suction force of the engine to operate the fuel interrupter by means of pneumatic pistons, pneumatic membranes, etc.

The pneumatic device communicates with the suction line of the engine, and an interrupting device is arranged between the latter and the 10 pneumatic device, to allow the cutting off of said communication or connection.

This last mentioned interrupting device may be actuated at will by the driver, or operated automatically at the right moment. Preferably, 15 it should operate at the moments when the degree of vacuum in the admission tube surpasses the degree of vacuum of the idling jet, viz; mainly when the car, due to the inertia and upon releasing the accelerator, drags the engine.

20 The object of these pneumatic devices controlling the interrupter is to give a rapid and total answer, in order to obtain an immediate closure of the interrupter, similar to the answers of the electro-magnetic control.

25 The invention has been illustrated in several embodiments in the accompanying drawings, wherein:—

Figure 1 is an assembly of the different elements constituting the apparatus subject of the 30 present invention, as well as their mutual relation and their relation with the engine organs.

Figure 2 is a sectional view of a modification in construction of the chamber C illustrated in Figure 1.

35 Figure 3 shows the chambers B and C assembled in a single body.

Figure 4 also shows a sectional view of a modification in construction of the assembly represented in Figure 3.

40 Figure 5 is a sectional view of a modification in construction of the chamber A.

Figure 6 is a sectional view of a further modification in construction of the chambers B and C.

The pneumatic chamber A comprises the casing 1, the flexible membrane 2, which carries 45 fixed thereto the metallic discs 3 by the center of which passes a screw 4 with its corresponding nut 5, for the purpose of suitably adjusting to each other the discs 3 and membrane 2.

50 The screw 4 has a central threaded conduit through which passes the screw 6.

The cavity 7 of the chamber A communicates with the main suction conduit of the engine, by means of a conduit 8.

55 The spring 9, bearing on one side against the

projecting flange 10, maintains the membrane 2 in correct operating position.

Through the action of the spring 12, the valve 11 bears against said projecting flange 10.

The cavity 7 communicates with the exterior 5 through the conduit 13.

The conduit 14 communicates this chamber with the pneumatic chamber B. Said pneumatic chamber B comprises mainly the casing 15, resilient membrane 16, metallic discs 17 and the screw 18 with its corresponding nut 19. The screw 18 extends to the exterior of the chamber B, and is provided with a screw 20 and nut 21, which fix the contact plate 22 and conductor 23.

The conductor 23 is connected to one of the 15 poles of the lamp 24, the other pole thereof being connected to the battery 25, which is in turn connected by its other pole to the casing 15 of the chamber B, by means of the conductor 26.

The screw 18 has at the end thereof an orifice or eye 27 for the purpose of passing a link 28 which joins same to the lever 29 having its fulcrum 30 fixed to the casing 31 of the chamber C. This chamber comprises mainly the flexible 25 membrane 32, screw 33, metallic disc 34 and nut 35. The screw 33 has its internal end rounded, so that on bearing against the orifice 36, it closes the communication between the conduit 31 leading to the idling jet 38, and the constant level 30 chamber 39.

The spring 40 is located in the interior of the chamber C.

The main injector 41 of a carburetor 42 and the control butterfly 43 have been schematically represented.

The operation of the devices described above is effected in the following manner:—

Upon operating the engine, the vacuum variations produced in same are transmitted through the conduit 8 to the pneumatic chamber A, and particularly influence the flexible membrane 2 which will oscillate according to the variations of the suction. When the suction has passed a predetermined limit, as, for example, when the vehicle is running at a certain speed and the accelerator is released, a sudden increase of vacuum is produced, which is higher than the normal degree of vacuum of the run with idling jet and the membrane 2 is suctioned, pushing the valve 11 by means of the end of the screw 6. At this moment the vacuum is suddenly transmitted to the pneumatic chamber B, attracting the membrane 16 and screw 18, which, on being displaced by means of the contacts 22, determines the

lighting of the lamp 24, at the same time drawing the internal end of the lever 29, closing the orifice 36 and therefore avoiding the passage of fuel from the idling jet to the cylinders.

- 5 When the vacuum of the engine decreases, the membrane 2 and the valve 11 return to their idle position, while at the same time the spring 40 carries the membranes 32 and 16 to their idle positions, the passage of fuel to the idling jet 10 being again established. The conduit 13 allows the return of the membrane 16 to its idle position.

Every time the passage of fuel to the idling jet has been interrupted, the lamp 24, arranged on 15 the dashboard, will indicate to the driver that said interruption has been effected.

By turning the screw 6, the driver may regulate the device so as to effect the interruption at a determined vacuum. And should the end of 20 said screw be sufficiently separated from the valve 11, the interrupting devices are placed out of operation.

The device illustrated in Figure 2 consists of the same elements corresponding to the chamber 25 C. This figure also shows the manner of adapting the interrupter to one type of carburetor. The screw 33 of Figure 1 is also provided with a stem 44 which slides within the tubular piece 45 having both ends threaded. Said piece 45 carries the guide 46 for securing the correct operation of the stem 44, and the orifices 47 for allowing the passage of the fuel to the conduit 31 of the idling jet. Figure 2 also illustrates with the reference numbers 48 and 49, the internal and external walls respectively of the naphtha conduit of a carburetor. 50 is a screw having a large central perforation, and 51 is a nut completing the 35 adjustment of the device.

Figure 3 illustrates the screw 52 which renders 40 the membranes 16 and 32 integral. The conduit 53 allows the communication with the chamber A by means of the conduit 14, shown in Figure 1.

As stated above, Figure 4 illustrates a modification 45 in construction which replaces, as a unit, the elements shown in Figure 3.

Said device comprises essentially a casing 54 having adapted in the interior thereof a flexible membrane 16, which carries fixed to its central 50 point a stem 55 ending in the valvular piece 56; said valve is intended to bear against the flange 57 formed on one of the sides and central portion of the casing 54. The conduit 37 communicates with the idling jet and the conduit 58 with the 55 constant level chamber. The spring 59 carries the membrane 16 and the valve 56 to their idle position.

The casing 54 is provided with a conduit 60 for 60 communication with the chamber A.

Figure 5 illustrates a hollow cylinder 61 provided with a conduit 62 for communicating the interior of the chamber with the suction line of the engine. Within same slides the piston 63, through the center of which passes the screw 64, and provided with a spring 65. The valve 66 bears against the flange 67. It also comprises the spring 68 and conduit 69. The conduit 70 communicates said chamber with the chamber B.

The operation of this device is similar to that 70 of the chamber A of Figure 1.

Figure 6 shows the cylindrical chamber 71, with its piston 72 provided with a stem 73, a spring 74 and a conduit 75, which communicates 75 this chamber with the chamber A. The stem is

provided with a tooth 74 intended to engage the plate 76.

This chamber is a further embodiment of the chamber B illustrated in Figure 1.

The link 28 joins the stem 73 with the stem 77 of the piston 78 which slides in the cylindrical chamber 79. The piston 78 is crossed through by the conduit 80. A spring 81 is located within the chamber. The conduit 82 is intended to communicate with the constant level chamber, 10 the conduit 83 communicates with the idling jet, and the conduit 84 communicates the chamber with the exterior.

This chamber is a modification in construction 15 of the chamber C illustrated in Figure 1.

The operation of these devices is similar to that described with reference to the chambers B and C illustrated in Figure 1.

Having now particularly described and ascertained the nature of the present invention, I declare that what I claim is:—

1. Automatic fuel interrupting device for explosion engines and the like, provided with a first pneumatic chamber communicating with the suction line of the engine, characterized in that said 25 chamber is coupled to a second pneumatic chamber controlling the interrupting device, both chambers being separated by a valvular device actuated by said first chamber, the fuel interruptions being produced upon the increases of the 30 vacuum in the suction line of the engine passing a predetermined degree.

2. Automatic fuel interrupting device for explosion engines and the like, provided with a first 35 pneumatic chamber communicating with the suction line of the engine, according to claim 1, characterized in that said chamber is coupled to a second pneumatic chamber controlling the interrupting device, both chambers being separated by a valvular device actuated by said first chamber, by means of a rigid stem fixed to the movable 40 wall of said pneumatic chamber which actuates said valvular device.

3. Automatic fuel interrupting device for explosion engines and the like, provided with a first 45 pneumatic chamber communicating with the suction line of the engine, according to claim 1, characterized in that said chamber is coupled to a second pneumatic chamber controlling the interrupting device, both chambers being separated 50 by a valvular device actuated by said first chamber, by means of a rigid stem threaded and screwed to the movable wall of said pneumatic chamber, said stem having a head which enables same to be screwed and unscrewed at will, for 55 the purpose of regulation.

4. Automatic fuel interrupting device for explosion engines and the like, provided with a first pneumatic chamber communicating with the suction line of the engine, according to claim 1, 60 characterized in that said chamber is coupled to a second pneumatic chamber controlling the interrupting device, both chambers being separated by a valvular device actuated by said first chamber, the second pneumatic chamber being provided with means communicating same with the 65 valvular fuel interrupting device.

5. Automatic fuel interrupting device for explosion engines and the like, provided with a first pneumatic chamber communicating with the suction line of the engine, according to claim 1, characterized in that said chamber is coupled to a second pneumatic chamber controlling the interrupting device, both chambers being separated 70 by a valvular device actuated by said first chamber.

ber, the lighting circuit of a control lamp being closed each time the fuel interrupting device is acting.

6. Automatic fuel interrupting device for explosion engines and the like, provided with a first pneumatic chamber communicating with the suction line of the engine, according to claim 1, characterized in that the second pneumatic chamber controls the interrupting device of the idling jet.

7. Automatic fuel interrupting device for explosion engines and the like, provided with a first pneumatic chamber communicating with the suction line of the engine, according to claim 1, characterized in that the second pneumatic chamber is constituted by a rigid wall and a further flexible wall, the movements of which actuate the fuel interrupting device.

8. Automatic fuel interrupting device for explosion engines and the like, provided with a first pneumatic chamber communicating with the suction line of the engine, according to claim 1, characterized in that the fuel interrupting device actuated by the second pneumatic chamber is constituted by a chamber having a rigid wall with inlet and outlet fuel orifices, and a further flexible wall having a shutter device which closes one of the fuel orifices when said membrane is actuated, thus interrupting the passage of the fuel.

9. Automatic fuel interrupting device for explosion engines and the like, provided with a first pneumatic chamber communicating with the suction line of the engine, according to claim 1, characterized in that the second pneumatic

chamber and the fuel interrupting device form part of a single piece, the respective movable walls of same being joined by means of a rigid stem.

10. Automatic fuel interrupting device for explosion engines and the like, provided with a first pneumatic chamber communicating with the suction line of the engine, according to claim 1, characterized in that the first or second pneumatic chamber is constituted by pneumatic pistons.

11. Automatic fuel interrupting device for explosion engines and the like, provided with a first pneumatic chamber communicating with the suction line of the engine, according to claim 1, characterized in that the fuel interrupting device is constituted by a piston moving within a cylinder.

12. Automatic fuel interrupting device for explosion engines and the like, provided with a first pneumatic chamber communicating with the suction line of the engine, according to claim 1, characterized in that the second pneumatic chamber is constituted by two compartments separated by a flexible wall, one compartment being in communication with the suction line of the engine, with the interpolation of a valvular device controlled by the first pneumatic chamber, and the other compartment being in communication with the fuel line, having a valve integral with said membrane, which interrupts the passage of fuel to the cylinders, preferably from the idling jet, when said membrane is actuated.
